UNITED STATES PATENT OFFICE.

WILLIAM STANLEY, JR., OF PITTSFIELD, MASSACHUSETTS.

ELECTRIC INDUCTIONAL TRANSFORMER.

SPECIFICATION forming part of Letters Patent No. 461,135, dated October 13, 1891.

Application filed January 16, 1891. Serial No. 377,946. (No model.)

To all whom it may concern:

Be it known that I, WILLIAM STANLEY, Jr., a citizen of the United States, and a resident of Pittsfield, in the county of Berkshire and State of Massachusetts, have invented certain new and useful Improvements in Electric Inductional Transformers, of which the following is a specification.

My invention relates to certain improvements in the mechanical and constructional details of that class of transformers usually employed in the distribution of electricity for illuminating and other like purposes. Such a transformer consists of primary and secondary coils of insulated copper wire, usually separately wound and separately insulated from each other and also from the mass of iron, technically termed the "core," upon which their inductive action is exerted. Experience has shown that a very efficient organization of such a transformer is obtained when the mass of iron constituting the core is formed of thin plates or laminae sufficiently insulated from each other to prevent the transmission from plate to plate of induced currents of low electro-motive force, and also when the mass of iron formed by assembling or grouping a considerable number of these plates together is made to completely envelop and inclose the copper-wire coils on every side. I have found by experiment that the efficiency of a transformer constructed in the general manner which I have described is considerably increased by permitting to the individual plates of the core an independent but restricted motion among themselves in response to the intermittent magnetic forces generated within them by the influence of alternating electric currents traversing the magnetizing coil.

The general object of my invention is to construct the transformer in such a manner as to render the plates capable of such independent movement and to admit of their independent adjustment under the pressure of the clamping devices by which the groups of plates are held together and secured.

The invention further contemplates such a construction and organization of the elementary parts of the transformer as will not only secure the results hereinbefore mentioned, but will permit of cheap construction

and economy of hand labor in the assemblage of the parts.

In the accompanying drawings, Figure 1 is a vertical transverse section of a transformer containing my improvements. Fig. 2 is a vertical longitudinal section of the same, and Fig. 3 is a perspective view, which exhibits more clearly the manner in which the groups of plates are assembled together.

Referring to Figs. 1 and 2, P and S represent the primary and secondary coils of the converter. These are preferably wound in the form of a rectangle with semicircular ends, bearing a general resemblance in form to one link of a chain formed of a square bar of metal. The primary coil P (see Fig. 1) is usually of comparatively thin wire and is wound outside the secondary coil S, which is composed of thicker wire. Instead of winding these coils upon a temporary form in the manner heretofore usually practiced, I prefer to permanently wind them directly upon a mass or group of plates C, which ultimately constitutes the central section of the completed core. This group is formed of thin laminae resembling in outline the cross-section of a bobbin, as seen at C, in Fig. 1. Each plate consists of a rectangular portion C, occupying the space within the inner coil S and having integral extensions c c, of triangular outline, projecting outside the magnetizing coil. The plates of this central group, being insulated from each other to the extent required in any well-known or suitable manner, are secured together by bolts f f, having suitable clamping-nuts upon their ends, as shown in the drawings. The insulated-wire coils having been thus wound on the central portion C of the sectional core, two exterior groups of plates of similar thickness C' and C² are applied thereto in such a manner as to complete a double magnetic circuit, surrounding both halves of the coils every side and leaving exposed only the semicircular portion at the ends. These two sections or groups C' and C² are composed of a sufficient number of thin plates of an arch or bridge shape, as seen in Figs. 1 and 3, the abutments of the arch or bridge being cut off or formed obliquely, as shown at c' c', so as to bear against the corresponding inclined or oblique edges of the central core at c c. At the mid-

dle of each arch or bridge is a saddle d , of insulating material, which transmits to the entire group or assemblage of plates the pressure of the arch-shaped clamps B B, one of which spans or incloses each of the exterior groups of plates. The two arch-shaped clamps are held together by the longitudinally-adjustable bolts and nuts b .

From the description hereinbefore given it will be understood that when the groups of plates are assembled together and the arch-shaped clamps B B put in place and properly secured by screwing up the bolts b the entire pressure of the clamping devices will be exerted upon the centers of the arch-shaped plates through the saddles d , and that this pressure will be exerted not upon the group as a unit, but separately upon each individual plate of the group, which will be therefore free to adjust itself in such manner as to endure the firmest possible contact of its inclined edges $c' c'$ against the corresponding opposite plate of the central core C, and, furthermore, it will be obvious that, being supported in this manner at three points, only upon the edges, each plate will yield to a limited but sufficient extent under the stress of the magnetic forces due to the action of the magnetizing coil when excited by an alternating current. The position of the three groups of plates with reference to each other will perhaps be best understood by an inspection of Fig. 3, which exhibits them in their relative positions in the completed transformer, the coil and the external clamping devices being omitted. After the parts are assembled together and properly clamped the apparatus may be placed within an inclosing metallic cylindrical shell or case E, having, preferably, a lining of insulating material. The terminals of the coils may be led out through this external shell in the usual manner, as shown in Fig. 2.

I claim as my invention—

1. A sectional transformer-core composed of detached plates or groups of plates held

loosely in their supports, so as to be capable of mutually-independent self-adjustment in planes substantially parallel with their respective surfaces.

2. In an electric transformer, a group of detached arch or bridge shaped plates bearing against abutments composed of integral plates grouped in like manner, said plates or groups of plates being held loosely in their supports, so as to be capable of mutually-independent self-adjustment when maintained in position by pressure exerted against the edges of the plates of which said group is formed.

3. A transformer-plate in the form of an arch or bridge spanning the magnetizing-coil, having oblique bearings at each end, and fitted with a saddle forming a third bearing at the center of the bridge.

4. In an electrical transformer, a core inclosing a magnetizing-coil and consisting of three sets or groups of plates, one set occupying the space between the opposite sides of the coil and inclosing said coil on three of its sides and the other two groups covering the remaining portions of the coil and completing the magnetic circuit, in combination with clamping devices for maintaining forcible contact between said groups of plates.

5. A sectional transformer-plate consisting of a rectangular central section inclosed within the magnetizing-coil and projecting therefrom on each side, in combination with two bridge-shaped sections spanning and inclosing the coil, and arch or bridge shaped clamps bearing against the exterior of the bridge-shaped sections at a central point and having their abutments united by longitudinally-adjustable clamps.

In testimony whereof I have hereunto subscribed my name this 14th day of January, A. D. 1891.

WILLIAM STANLEY, JR.
